UNITED STATES PATENT OFFICE.

PAUL SCHWARZENHOELZER, OF BUFFALO, NEW YORK.

PARING AND SLICING DEVICE.

SPECIFICATION forming part of Letters Patent No. 323,451, dated August 4, 1885.

Application filed April 6, 1885. (No model.)

To all whom it may concern:

Be it known that I, PAUL SCHWARZENHOELZER, a subject of the Emperor of Germany, residing at Buffalo, in the county of Erie and State of New York, have invented 5 certain new and useful Improvements in Paring and Slicing Devices, of which the following is a specification.

The object of my invention is to produce a 10 small portable device for paring and slicing potatoes, radishes, or other similar articles of food; and it consists of a slicing-knife provided with a screw for drawing it into the material to be sliced, a suitable handle, and a 15 paring-knife mounted on a spring, all of which will be fully and clearly hereinafter shown, described, and claimed by reference to the accompanying drawings, in which—

Figure 1 is a side elevation. Fig. 2 is a top 20 view, looking toward the back of the knife; and Fig. 3 is an end view, looking toward the end of the knife and cutter..

In said drawings, *a* represents the slicing-knife. It is provided with a ring or handle, 25 *a'*, and *a''* is the cutting-edge. To one side of the knife, near the ring or handle, are two projecting pieces, *a³* *a⁴*, between which the bent end of the spring *a⁵* is jointed by a pin or rivet, *c*, so that the spring is capable of a 30 slight movement sidewise back and forth. To the opposite end of the spring is a small paring-knife or cutter *c'*. It is represented as rigidly secured to the spring, but may be made separate and secured in any well-known way

by a screw.. At the end of the slicing-knife 35 is rigidly secured a pointed screw, *c''*.

The operation of the invention will be easily understood by reference to the drawings. A potato, radish, or other vegetable is put onto the screw *c'*, as shown by the dotted lines *c³*, 40 the spring and paring-knife being moved so as to rest against the outside of the same, as shown by the dotted lines *c⁵* in Fig. 1. If the slicing-knife is now turned, by placing the finger in the ring *a'*, it will cut a spiral slice 45 through the vegetable as fast as the screw draws it down. (The slicing-knife is also inclined slightly, as shown in Fig. 3, so as to assist the screw.) At the same time the paring-knife cuts a narrow strip, or peels as fast 50 as the slicing-knife cuts it away.

I am aware that a knife having a ring at one end, by which it is operated, and a screw at the opposite end, is not new. I therefore do not claim such, broadly; but 55

What I do claim is—

A paring and slicing device consisting of a slicing-knife provided with a handle at one end and a pointed screw at the opposite end, 60 in combination with a spring, *a⁵*, secured to the knife, and provided with a paring-knife, *c'*, substantially as and for the purposes described.

PAUL SCHWARZENHOELZER.
